HANGER ATTACHMENT FOR LADIES' GARMENTS

Joseph B. Potoczky, Silver Spring, Md.

Application July 7, 1944, Serial No. 543,885

6 Claims. (Cl. 223—88)

This invention relates to new and useful improvements in garment hangers and more particularly to an attachment which can be applied to conventional hangers for the purpose of positively hanging ladies' garments, such as undergarments by their shoulder straps.

At present, it is very difficult to suspend ladies' undergarments on conventional hangers by their shoulder straps due to the tendency of the straps to slip off of the ends of the hangers, and with this in view, it is the principal object of the present invention to provide a small inexpensive attachment which can be almost instantly applied to conventional wire hangers so as to provide hooks into which the shoulder straps of ladies' garments can be inserted for positively retaining the garments against displacement.

Other objects and advantages of the invention will become apparent to the reader of the following description.

In the drawing:

Figure 1 is a front elevational view of a conventional hanger showing the attachment applied.

Figure 2 is an enlarged elevational view showing the grooved side of one of the attachments.

Figure 3 is an edge elevational view of one of the attachments.

Figure 4 is a cross-sectional view taken substantially on the line 4—4 of Figure 3.

Referring to the drawing wherein like numerals designate like parts, it can be seen that numeral 5 generally refers to a conventional wire hanger which consists of a single length of wire bent to provide a horizontal member 6, sloping shoulder portions 7, 7 and a hook 8.

On each end of such a hanger, an attachment 9 (the present invention) can be easily applied for the purpose of engaging the shoulder straps A of a lady's undergarment B as is clearly shown in broken lines in Figure 1.

It is preferable that the attachment 9 be made of plastic, but, of course, the same can be made of any suitable material and color to meet the demands of the buying public.

The attachment consists of an elongated block 10 preferably cut off on an oblique at one end as at 11 and having its opposite end rounded off as at 12 and projecting beyond one longitudinal edge as at 13. At this portion of the block, the block is formed with a groove 14 extending inwardly approximately half way across the width of the block and one side of this groove 14 forms one side of the projecting portion 13, the groove 14 and projecting portion 13 defining a hook or ledge

upon which the shoulder straps A can rest, in contrast to the sloping portion 7 of a conventional hanger.

The body 10 of the attachment further consists in being formed with a transverse groove 15 adjacent the groove 14. This groove 15 is substantially deep to receive the horizontal portion 6 of the conventional hanger and has small lips 16 alternately placed on opposite side portions thereof. The body 10 is formed with grooves 17, one at each side of the groove 15, the grooves 17 not being deep as the groove 15, but allowing for the flexion of the body 10 at the lips 16. In other words, when the body 10 is pressed against, for instance, the portion 6 of the hanger and pressure is exerted against the lips 16, that portion of the material of the attachment will flex due to the presence of the grooves 17 and allow the space of the groove 15 to widen sufficiently to accept the horizontal member 6 of the hanger.

The upper portion of the body 10 is likewise provided with an obliquely disposed groove 15a, lips 16a and lateral shallower grooves 17a to accommodate the corresponding sloping portion 7 of the conventional hanger.

It has been found that due to the resilient nature of plastic, plastic is a very suitable material for the construction of these attachments.

The attachment can be constructed very economically and can be retailed at a very low price.

The depth of the grooves 15, 15a may necessitate the provision of reinforcing ribs 18 molded of the same material, along the back side of the body 10, as is suggested in Figure 3.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A hanger attachment of the character described comprising a body provided with a garment engaging means and formed with grooves for receiving portions of a triangular wire hanger, said body being formed with shallower grooves adjacent said first mentioned grooves to increase the flexibility of the body at said first-mentioned groove.

2. A hanger attachment of the character described comprising a body provided with a garment engaging means, and formed with grooves for receiving portions of the triangular wire hanger, said body being formed with shallower

grooves adjacent said first mentioned grooves to increase the flexibility of the body and said first-mentioned grooves, and wire gripping protuberances on opposite edges of said first-mentioned grooves.

3. A hanger attachment of the character described adapted to be secured to a wire coat hanger of triangular configuration, comprised of a resilient body portion of polygonal configuration having grooves therein, one of said grooves being disposed in non-parallel relation to the other, one groove being adapted to engage the wire at the base of the coat hanger and the other one of said grooves to engage one of the legs of the triangular coat hanger in such manner as to preclude linear movement of the body portion on the base of the coat hanger, and garment supporting means depending from the lower portion of said body.

4. A hanger attachment of the character described adapted to be secured to a wire coat hanger of triangular configuration, comprised of a resilient body portion of polygonal configuration having grooves therein, one of said grooves being disposed in non-parallel relation to the other, one groove being adapted to engage the wire at the base of the coat hanger and the other one of said grooves to engage one of the legs of the triangular coat hanger in such manner as to preclude linear movement of the body portion on the base of the coat hanger, and garment supporting means depending from the lower portion of said body, said garment supporting means comprising a hook so dimensioned as to project laterally beyond the extremities of the base of the coat hanger when the attachment is positioned thereon.

5. A hanger attachment of the character described adapted to be secured to a wire coat hanger of triangular configuration, comprised of a resilient body portion of polygonal configuration having grooves therein, one of said grooves being disposed in non-parallel relation to the other, one groove being adapted to engage the wire at the base of the coat hanger and the other one of said grooves to engage one of the legs of the triangular coat hanger in such manner as to preclude linear movement of the body portion on the base of the coat hanger, said body portion being formed with shallower grooves adjacent said first-mentioned grooves to increase the flexibility of said body at the first-mentioned grooves, and garment supporting means depending from said body portion.

6. A hanger attachment of the character described adapted to be secured to a wire coat hanger of triangular configuration, comprised of a resilient body portion of polygonal configuration having grooves therein, one of said grooves being disposed in non-parallel relation to the other, one groove being adapted to engage the wire at the base of the coat hanger and the other one of said grooves to engage one of the legs of the triangular coat hanger in such manner as to preclude linear movement of the body portion on the base of the coat hanger, said body portion being formed with shallower grooves adjacent said first-mentioned grooves to increase the flexibility of said body at the first-mentioned grooves, said grooves having wire gripping protuberances on the opposite sides thereof, and garment supporting means depending from the lower portion of said body.
